FIG.1

FIG.3

FIG. 4

Figure 1 is a side elevation view of a lantern showing our new design with the battery fragmentarily shown for convenience of illustration.

Figure 2 is a front elevational view thereof as shown in Fig. 1.

Figure 3 is a rear elevational view thereof as shown in Figure 2.

Figure 4 is a slightly enlarged perspective view thereof showing the rear lamp in its elevated position.

The dominant features of our design reside in the portions shown in full lines.

We claim:

The ornamental design for a lantern, as shown and described.
